United States Patent Office.

JOHN A. HEYL, OF BOSTON, MASSACHUSETTS, ASSIGNOR TO HIMSELF AND
JOHN H. WIGGINS, OF SAME PLACE.

Letters Patent No. 80,074, dated July 21, 1868.

IMPROVEMENT IN HORSE-SHOES.

The Schedule referred to in these Letters Patent and making part of the same.

TO ALL PERSONS TO WHOM THESE PRESENTS MAY COME:

Be it known that I, JOHN A. HEYL, of Boston, in the county of Suffolk, and State of Massachusetts, have made a new and useful Invention for Securing a Shoe to the Hoof of a Horse; and I do hereby declare the same to be fully described in the following specification and represented in the accompanying drawings, of which—

Figure 1 is a top view,

Figure 2 a side elevation,

Figure 3 a front elevation of a hoof and shoe with my invention connecting the two.

Figure 4 is a top view, and

Figure 5 a side elevation of the connection.

Figure 6 is a top view,

Figure 7 a longitudinal section, and

Figure 8 a front view of the shoe, as made, for being held to the hoof by the connector, as hereinafter explained.

The said shoe, shown at A, has three shallow recesses, *a b b*, arranged in or below its upper surface, in manner as represented, one being at the toe and the others being near its heels.

The opposite edges of the recess *a* are inclined with the base of the recess, in manner as shown at *e e* in fig. 8, and also in Figure 9, which is a transverse section of the shoe, such section being taken through the middle of the recess *a*.

Each heel-recess, *b*, is right angular in shape, and has one edge, *d*, inclined to the base or bottom of the recess in manner as shown at *e e* in Figure 10, which is a transverse section of the shoe, it being taken through the recesses *b b*.

Furthermore, a standard, *f*, having a screw, *g*, screwed through it, is erected on the shoe at its toe.

The connector B consists of two jaws, *h h*, formed to clasp the sides of the hoof C, and provided with catches *i i*, *k k*, which project from the jaws, and are shaped in manner as represented. The two catches *i i* are hinged together, as shown at *l*, and have their outer edges bevelled, as shown at *m m*, to extend under the inclined edges, *e e*, of the recess of the toe of the shoe.

The outer edges, *n n*, of the heel-catches *k k* are also bevelled so as to catch under the inclined parts, *e e*, of the heel-recesses of the shoe.

In fixing the shoe to the hoof by means of the connector, the jaws of the latter should be opened apart as far as possible, and the hoof introduced between them. Next, the shoe should be pressed up against the catches of the connector, so as to cause the jaws to close upon the hoof and the catches to take into the recesses of the shoe, and catch therein, and hold it close up to the hoof. Next, the screw *g* should be screwed up so as to pass over the hinge *l* of the catches *i i*, and thereby hold the shoe locked to the connector.

Thus the shoe may be fastened to the hoof without the necessity of nailing it thereto, and at any time may be easily removed therefrom, particularly when it may be desirable to have the horse stand in the stable or run in a pasture without any shoes on his hoofs.

I claim as my invention the following; that is to say—

I claim the connector B, as described, that is, as consisting of the jaws and toe and heel-catches, arranged, constructed, and combined substantially in manner and to operate with a hoof and with a shoe, constructed essentially as set forth.

I also claim the shoe as made or provided with toe and heel-catch recesses to receive the catches of the jaws of the connector B, constructed as described.

I also claim the combination and arrangement of the standard *f* and its screw *g* with the shoe, provided with toe and heel-recesses to receive the connector B, made substantially as described.

I also claim the combination of the standard *f* and its screw *g* with the shoe A and the connector B, made in manner and so as to operate together substantially as specified.

JOHN A. HEYL.
